UNITED STATES PATENT OFFICE.

ANTON KARL MASSA, OF NEW YORK, N. Y., ASSIGNOR OF ONE-HALF TO SAMUEL DUBROWIN, OF NEW YORK, N. Y.

SAFETY-PIN.

1,262,537.

Specification of Letters Patent. Patented Apr. 9, 1918.

Application filed November 24, 1917. Serial No. 203,736.

To all whom it may concern:

Be it known that I, ANTON K. MASSA, a subject of the King of Austria, and a resident of the city of New York, borough of 5 Manhattan, in the county and State of New York, have invented a new and Improved Safety-Pin, of which the following is a full, clear, and exact description.

An object of the invention is to provide 10 a simple, inexpensive and efficient pin which will not become unlocked accidentally.

Another object of the invention is to provide 15 a spring-actuated catch which will retain the end of the pin and prevent an accidental disengagement of same from the hook on which the catch is provided.

With the above and other objects in view, 20 the nature of which will more fully appear as the description proceeds, the invention consists in the novel construction, combination and arrangement of parts as herein 25 fully described, illustrated and claimed.

In the accompanying drawings, forming 30 part of the application, similar characters of reference indicate corresponding parts in all the views.

Figure 1 is a side elevation of a pin embodying my invention;

Fig. 2 is an end elevation of the pin;

Fig. 3 is a perspective view of the catch; 35 Fig. 4 is a section through the lock on line 4—4, Fig. 8;

Fig. 5 is a perspective view of the locking spring;

Fig. 6 is a horizontal cross section on line 40 6—6, Fig. 2;

Fig. 7 is a section similar to that shown 45 in Fig. 4 to show the catch displaced when removing or introducing the end of the pin into the lock; and

Fig. 8 is an enlarged side elevation of the lock and pin engaged therein.

Referring to the drawings, 9 is a pin pivotally connected at one end to a lug 10 rising from a plate 11 which is adapted to carry the ornamental part of the pin. The plate 11 also carries a hook 12 into which the sharp end of the pin is adapted to enter.

A catch 13 is mounted pivotally in the hook 50 to form the snap for same. The catch has a flat surface 14 which rests against the straight side of a spring 15 which is located in a slot 16 provided in the hook. The slot 16 is bridged between the ends near the rear 55 of the hook, as shown at 17. The spring

15 has a recess 18 for engaging the bridge 17, whereby said spring is maintained in position in the hook.

The engagement of the flat surface 14 with the spring maintains the arm 19 of the catch 60 against the end of the hook, thereby closing the entrance to the hook. The catch has also a shorter arm 20, so to say, formed by the flat surface and the recess. This shorter arm is adapted to engage the end of the hook 65 and thereby limit the outward movement of the catch. The purpose of this arrangement is to bridge the opening in the hook in case the spring 15 breaks.

To disengage the pin from the lock the 70 same is pressed toward the recess in the catch and outwardly of the hook. The pressure applied to the longer arm of the catch by this movement displaces the catch on its pivot against the resistance of the spring 75 15 thereby moving the arm away from the hook and permitting the withdrawal of the pin (see Fig. 7). To introduce the pin into the hook the pin is brought on to the hook and moved against the arm 19 of the catch. 80 The end of the arm is cut on the bias so as to form a V groove with the curved surface of the hook. In consequence the pin forms a wedge which forces the arm 19 of the catch away from the hook surface against 85 the resistance of the spring and allows the pin to enter the hook (see Fig. 7).

From the above description it will be seen that my lock is a snap hook in which the snap or catch has an outside arm extending 90 beyond the gap in the hook, and which arm is maintained against the hook by a yielding member. This snap has also an inner arm the length of which is such that it will bridge the opening of the hook if the same 95 is moved against the end of the hook. If the spring breaks and the inner arm is free to move it will come in contact with the end of the hook and will bridge the opening, thereby preventing an accidental disengagement of the pin with the hook. 100

I claim:

1. A safety pin comprising an ornament carrier, a pin foldable to and from the ornament carrier, a hook on the carrier for receiving the end of the pin, a snap pivotally connected to the hook to present an outer arm adapted to be moved against the end of the hook, said hook having a bridged slot, and a spring in said slot engaging the 110

- bridge, said spring bearing against the snap and normally maintaining the arm of same against the end of the hook whereby the hook opening is bridged by said snap.
5. A safety pin comprising an ornament carrier, a pin pivotally connected to the carrier, a slotted hook on said carrier for receiving the end of the pin, a spring in the slot of the hook, a bridge in said slot of 10 the hook engaging the spring and whereby the spring is retained in the slot, and a snap pivotally connected to the hook so as to engage the spring, said spring normally forcing the end of the snap against the outer 15 face of the end of the hook.
3. A safety pin comprising an ornament carrier, a pin pivotally connected to the carrier, a hook on the carrier for engaging the end of the pin, a spring-actuated snap in 20 said hook having an outer and an inner arm, the inner arm of said hook being long enough to bridge the opening of the hook, the outer arm being normally in contact with the outer face of the end of the hook.
25. 4. A safety pin comprising an ornament carrier, a pin pivotally connected thereto, a hook on the carrier engaging the end of the pin, a snap pivotally connected to said hook

and having an inner and an outer arm, and a spring in said hook for engaging the snap so that the outer arm is normally maintained against the end of the hook and the inner arm against the spring, the inner arm of said snap being long enough to engage the end of the hook and bridge the opening 35 in the same.

5. A safety pin comprising an ornament carrier, a pin pivotally connected to the carrier, a hook on the carrier for receiving the end of the pin, said hook having a slot 40 in the plane of the hook, a member bridging said slot, a spring in said slot having a recess engaging the bridge and a snap pivotally connected to the hook and presenting an outer and an inner arm and engaging the 45 spring which normally tends to maintain the arm of the snap against the outer face of the end of the hook, said outer arm being adapted to be normally maintained in proximity of the spring, said outer arm tapering 50 at its end to form a V-shaped groove with the curved surface of the hook whereby the spring may be caused to displace the arm when brought into the groove formed by the arm and the curved surface of the hook. 55

ANTON KARL MASSA.
